UNITED STATES PATENT OFFICE.

I. ADDISON BUSH, OF PHILADELPHIA, PENNSYLVANIA.

MUCILAGE-HOLDER.

SPECIFICATION forming part of Letters Patent No. 388,823, dated September 4, 1888.

Application filed May 17, 1888. Serial No. 274,141. (No model.)

To all whom it may concern:

Be it known that I, I. ADDISON BUSH, a citizen of the United States, residing at Philadelphia, in the county of Philadelphia and State of Pennsylvania, have invented certain new and useful Improvements in Mucilage-Holders; and I do declare the following to be a full, clear, and exact description of the invention, such as will enable others skilled in the art to 5 10 15 20 25 30 35 40 45 50 55 60 65 70 75 80 85 90 95 100 which it appertains to make and use the same, reference being had to the accompanying drawings, and to the letters and figures of reference marked thereon, which form a part of this specification.

15 My invention relates to holders for mucilage and kindred liquids; and it consists in a detachable cover for the mucilage-receptacle, having a central perforated tube, means for adjusting the sponge, and other features, which 20 25 30 35 40 45 50 55 60 65 70 75 80 85 90 95 100 are fully set forth in the following description, and specifically pointed out in the claims.

The accompanying drawings illustrate the invention, its various features being shown in the different views.

25 Letters of reference are used to indicate its parts, similar letters denoting corresponding parts in the different figures.

Figure 1 is a side elevation of the invention, the cap being lifted off the bottle. Fig. 2 is a 30 vertical section of the tubular top. Fig. 3 shows one form of the mucilage duct or tube. Fig. 4 is a plan view of the bottom of the cover. Fig. 5 shows an elastic ring.

The letter B indicates a mucilage-receptacle, preferably made with a neck, b, having a 35 threaded exterior.

A denotes the cover of the bottle. Its lower 40 interior portion, a, is threaded to screw upon the neck b. The top C of this cover has a central vertical threaded opening, c.

D is a duct or tube having an exterior thread, d, adapted to engage the thread in the aperture c. When desired, the tube D may be soldered to the top C or cast in one piece with it. 45 I make the tubes D of different sizes to secure a flow of varying quantities of mucilage. In order to adapt them to the openings c, which are of one size, I form on the smaller tubes an annular threaded projection or ridge, a', of sufficient breadth to engage the thread in the opening c. Several small holes e e are made

through the sides of the tube just above its place of contact with the top C.

F is a sponge or porous filling of any preferred material placed in the tube D, and projecting sufficiently above it to serve as a brush for spreading the mucilage. Two slots, i i, are made in the lower part of the tube, and a pin, f, passed through the sponge and resting in these slots, keeps the sponge in place. The slot admits of some variation in the length of the exposed part of the sponge by allowing the sponge to be drawn out or pressed back farther into the tube. Other holes, h h, are provided for the pin f when the top of the sponge is 65 worn off and it needs to be drawn out farther than the slot would permit.

A compressible ring or washer, G, preferably of cork, is fitted into the cap A and rests against the top C. This ring prevents leakage 70 when the edge of the bottle neck is uneven. H is a rim around the cover A. It projects above its top C. The cap I protects the cover and prevents evaporation from the sponge.

In using this invention, having supplied the 75 bottle with mucilage, screw the cap snugly down upon the bottle neck, pressing the ring G closely against the top of the neck. This will prevent the liquid from getting into the thread of the cover or neck and from soiling 80 the bottle. On removing the cap and inverting the bottle the mucilage enters the duct, soaks through the sponge, and appears at its projecting end. When the bottle is righted after using, any overflow from the sponge is 85 retained within the rim H and returns into the duct through the openings e e, so that the cap I and the sides of the cover A are not soiled or stuck together by the adhesive, as in other mucilage-holders.

The dotted line n in Fig. 3 indicates the lower 90 end of the tube when the device for adjusting the sponge is not used.

I am aware that self-feeding mucilage-holders are not new, and do not broadly claim such 95 as my invention; but

What I do claim, and desire to secure by Letters Patent of the United States, is—

1. A mucilage-holder formed of a receptacle having a threaded neck, a threaded cover 100 having an annular rim, and whose top has a threaded vertical opening, a threaded tube

adapted to screw into said opening and having lateral perforations above said top, and a cap, substantially as herein set forth.

2. A mucilage-holder formed of a bottle and
5 a cover adapted thereto, the said cover having
a rim about its upper edge and a vertical tube
through its top, lateral perforations in the said
tube above the cover-top and opposite vertical
slots near its lower end, a porous filling for
10 said tube projecting above its top and held in
place by a pin passing through it and the said
slots, a compressible ring in the cover, and a
cap, substantially as herein described.

3. A cover for mucilage-holders, having a central threaded opening, and a tube or duct, 15 D, having a threaded portion, d, perforations e e, slots i i, and holes h h, for the purposes herein described.

In testimony whereof I affix my signature in presence of two witnesses.

I. ADDISON BUSH.
